M. MARKKULA.
STAKE FOR FLAT CARS.
APPLICATION FILED JULY 1, 1921.

1,398,441.

Patented Nov. 29, 1921.

UNITED STATES PATENT OFFICE.

MATT MARKKULA, OF FORT BRAGG, CALIFORNIA.

STAKE FOR FLAT-CARS.

1,398,441.

Specification of Letters Patent. Patented Nov. 29, 1921.

Application filed July 1, 1921. Serial No. 481,983.

To all whom it may concern:

Be it known that I, MATT MARKKULA, a citizen of the United States, residing at Fort Bragg, in the county of Mendocino and State of California, have invented certain new and useful Improvements in Stakes for Flat-Cars, of which the following is a specification.

This invention relates to stakes for flat cars, and it comprises a stake having an extension adapted to be received between a pair of guides carried by the car, the ends of the guides being offset to dispose the stake in inoperative position when it is moved toward the side of the car, and means for retaining the stake in operative position.

In the present invention, I have provided an improvement over the construction shown in my prior Patent No. 1,346,836, dated July 20, 1920. In the prior patent, I disclose a car stake which is pivotally mounted and in which a flexible element is secured on each side of the stake, the flexible element being attached to a locking bar extending transversely of the car to permit operation of the stake from the opposite side of the car.

In the present invention, I also provide a stake which may be operated from the opposite side of the car to that on which the logs are being loaded or unloaded. The invention comprises a pair of stakes arranged opposite each other and adapted to be received in guideways having offset ends. A locking bar is attached to each of the stakes and extends transversely of the car, a chain or other suitable device being secured to the end of the locking bar and being adapted to be received in a locking member to retain the stake in operative position. When the car is to be unloaded, the locking member is released and the weight of the log moves the stake outwardly on the guides. The stake passing over the offset end of the guide assumes an inoperative position below the top of the bunk or bolster and permits the logs to be unloaded.

The provision of a locking device operative from the opposite side of the car permits the stakes to be released without danger of the logs injuring the operator.

In the accompanying drawings, I have shown one embodiment of the invention. In this showing:

Figure 1 is a plan view of a portion of a car showing the stakes in position.

Fig. 2 is a transverse sectional view on line 2—2 of Fig. 1.

Fig. 3 is a side elevation of a portion of a car showing the position of the stake, and,

Fig. 4 is a vertical sectional view on line 4—4 of Fig. 1.

Referring to the drawings, the reference numeral 1 designates the side sills or beams of the car. A plurality of longitudinal beams 2 are arranged between the side sills 65 and transverse bunks or bolsters 3 are provided at suitable intervals.

Each of the stakes is arranged between a pair of transverse bunks or bolsters. As shown, the stake 4 is substantially triangular 70 in shape, and comprises a body portion 5, having a flange 6 formed on two sides. The ends of the flange are rounded, as at 7 and 8, forming bearings engaging the guides 9. The body portion of the stake is provided 75 with an extension having a transverse member 10 arranged below the guides. It will be apparent that the stake is slidably secured on the guides 9. The guides are carried by a block or casting having side plates 80 11 and top plates 12, adapted to be secured to the transverse beams of the car in any suitable manner. The side plates are connected at the bottom by a cross plate 13. As shown, the guides extend outwardly from 85 the side plates and are provided with a horizontal portion 14 arranged slightly below the surface of the beam. Adjacent the outer end, the guide is provided with a sloping portion 15, and a horizontal offset portion 90 16. The casting is provided with an end plate 17, having a recess 18 formed at the upper end thereof.

A locking rod 19 is secured to each of the stakes, and extends toward the opposite side 95 of the car. A chain 20 is secured to the other end of the locking rod, and this chain is adapted to be passed through an opening 21 in the end plate. A locking member or latch 22 is pivotally mounted on the end plate, as at 23, the locking member being provided with a slot 24 for the reception of one of the links of the chain. The end of the latch is offset, as at 25, which end may be struck with a hammer or other implement to move the latch to open or closed position.

The operation of the device is as follows:

When the stake is to be arranged in operative position, it is disposed on the hori-

zontal portion 14 of the guides, the chain 20 is pulled through the opening 21 and the latching member 22 arranged in locked position in engagement with the chain. 5 Further inward movement of the stake is prevented by means of stops 26 formed on the inner ends of the guides. When the logs are to be removed from the car, the locking member on one side is released to release the 10 stake on the opposite side. The stake is moved outwardly by the weight of the logs to the dotted line position shown in Fig. 2 of the drawings, with the extension 10 disposed on the sloping portion 15 of the 15 guides and the stake is arranged in the space between the guides and the top of the car. This permits the logs to roll off the side of the car.

It is to be understood that the form of my 20 invention herewith shown and described is to be taken as a preferred example of the same, and that various changes in the shape, size, and arrangement of parts may be resorted to without departing from the spirit of the 25 invention or the scope of the subjoined claims.

Having thus described my invention, I claim:

1. The combination with a flat car, of a 30 guide arranged below the surface of the car, said guide comprising a substantially horizontal portion, a sloping portion connected thereto, and an offset end substantially parallel to said horizontal portion, a 35 stake slidably mounted on said guide whereby the stake is retained in operative position when in engagement with a horizontal portion of the guide, and in inoperative position when in engagement with the offset end 40 thereof, and means for retaining said stake in operative position.

2. The combination with a flat car, of a guide comprising a pair of spaced members

arranged below the surface of the car, said members being arranged substantially horizontal throughout a portion of their length, sloping portions connected to said horizontal portions, offset ends connected thereto and arranged substantially parallel to said horizontal portions, a stake arranged above said members, said stake being provided with an extension engaging the underside of said members to slidably support the stake thereon, and means for retaining said stake in engagement with the horizontal portion of said members.

3. The combination with a flat car, of a guide arranged below the surface of the car, said guide comprising a substantially horizontal portion, a sloping portion connected thereto, an offset end connected to said sloping portion, said offset end being substantially parallel to said horizontal portion, a stake slidably mounted thereon, a rod secured to said stake, a chain secured to said rod, and means for locking said chain to retain said stake in engagement with the horizontal portion of the guide.

4. The combination with a flat car, of a stake mounted thereon, said stake comprising a substantially triangular body portion having an extension formed on the base thereof, a curved sloping guide secured to the car and engaging said stake between the base and the extension, said stake being adapted to assume an operative position when disposed inwardly of the guide and an inoperative position when disposed outwardly of the guide, and means for retaining said stake in operative position.

In testimony whereof I affix my signature in presence of two witnesses.

MATT MARKKULA.
